UNITED STATES PATENT OFFICE.

OSCAR D. HOLLENBECK, OF RACINE, WISCONSIN, ASSIGNOR TO RACINE HORSESHOE TIRE COMPANY, OF RACINE, WISCONSIN, A CORPORATION OF WISCONSIN.

DESIGN FOR A VEHICLE TIRE TREAD.

Application filed November 28, 1922. Serial No. 4,434. Term of patent 14 years.

To all whom it may concern:

Be it known that I, OSCAR D. HOLLENBECK, a citizen of the United States of America, residing at Racine, county of Racine, State of Wisconsin, have invented a new, original, and ornamental Design for a Vehicle Tire Tread, of which the following is a specification, reference being had to the accompanying drawings, forming part thereof.

In the drawings:

Fig. 1 shows in plan view a section of a tire embodying a tread of my new design.

Fig. 2 is a section on the line 2—2, Fig. 1.

I claim:—

The ornamental design for a vehicle tire tread, substantially as shown.

OSCAR D. HOLLENBECK.
